United States Patent Office

Des. 193,264
Patented July 24, 1962

193,264

VACUUM CLEANER

John J. Kelnhofer, Ontario, Calif., assignor to Fabimagic, Inc., a corporation of California

Filed Apr. 6, 1961, Ser. No. 64,637

Term of patent 14 years

(Cl. D9—2)

FIG.1.

FIG.2.

FIG.3.

FIG.4.

FIG.5.

I claim:

The ornamental design for a vacuum cleaner, substantially as shown and described.
